OFFSHORE WELL DRILLING APPARATUS
Glenn D. Johnson, Downey, and Bruce J. Watkins, Palos Verdes Estates, Calif., assignors to Shell Oil Company, New York, N.Y., a corporation of Delaware
Filed Sept. 11, 1963, Ser. No. 308,267
6 Claims. (Cl. 166—66.5)

This invention relates to the drilling of oil and gas wells, and pertains more particularly to a method and apparatus for drilling offshore wells wherein the wellhead assembly is positioned on the ocean floor or a considerable distance under the surface of a body of water.

During recent years the continued search for oil has resulted in developing methods and apparatus for drilling underwater wells at locations where the water may range from 100 to 1500 feet or more in depth. In these locations it is customary to position the wellhead at a considerable distance below the surface of the water, preferably on the ocean floor, so that it is not a hazard to the navigation of ships in the area. During well drilling operations it is often necessary to suspend two or more concentric strings of pipe casing or tubing from a drilling structure or vessel on the ocean surface with the pipe and tubing extending down into the well drilled in the ocean floor. A problem arises in providing the necessary pipe engaging and pipe supporting apparatus on the crowded operating floor of a drill rig in order to safely and adequately temporarily suspend multiple concentric strings of pipe.

A primary object of the present invention is to provide offshore well drilling apparatus whereby multiple concentric strings of pipe extending from an underwater well to a point above the surface of the ocean may be individually engaged and supported in a temporary manner.

A further object of the present invention is to provide a drilling vessel having multiple operating decks provided with apparatus for suspending each of a pair of concentric pipe strings from a separate operating deck of the vessel.

Another object of the present invention is to provide a drilling vessel with suitable pipe supporting apparatus whereby a string of casing may be suspended from one deck and extend into an underwater well while a drill string extends from a second deck through the casing and in the well.

These and other objects of this invention will be understood from the following description taken with reference to the drawing, wherein:

FIGURE 1 is a diagrammatic view illustrating a floating drilling vessel position over a drilling location while supporting concentric strings of pipe therefrom;

FIGURE 2 is a longitudinal fragmental view diagrammatically illustrating another arrangement of suspending concentric pipe strings from the vessel illustrated in FIGURE 1;

FIGURE 3 is a fragmental view taken in longitudinal cross section illustrating two forms of pipe supporting equipment adapted to be used on the drilling vessel of FIGURE 1;

FIGURE 4 is a view taken in longitudinal cross section illustrating the lower pipe support on the auxiliary deck of FIGURE 3 when raised to its vertical non-operative position; and

2

FIGURE 5 is a plan view of the pipe support structures on the lower or auxiliary deck of the vessel as shown in FIGURE 3.

Referring to FIGURE 1 of the drawing, an offshore structure for carrying out well drilling, completion and workover operations is shown. A drilling barge, vessel, or platform 11 of any suitable floating or floatable type is illustrated as floating on the surface of a body of water 12 and fixedly positioned over a preselected drilling location by being anchored to the ocean floor by anchor lines 14 and 15 running to anchors (not shown). Equipment of this type may be used when carrying on well drilling operations in water varying from about 100 feet to 1500 feet or more. The drilling vessel is equipped with a suitable derrick 16 containing a fall line system, including a travelling block 17, a hoist 18, a drilling swivel and/or an elevator 19. The barge 11 is also provided with other auxiliary equipment needed during the drilling of the well, such for example as a rotary table 20 positioned on the operating deck 21, a hinged slip-and-spider assembly 22 positioned on the lower deck 23, etc. The elevator 19 is normally provided for suspending therefrom, during certain of the drilling operations, a drill string 24 or the kelly section at the top of the drill string while the slip-and-spider assembly 22 is adapted to secure fixedly a string of pipe, for example, a string of surface casing 25 against a vertical movement relative to the vessel 11.

During the actual drilling operations during which the kelly at the upper end of the drill string 24 is positioned in and rotated by the master bushing 26 in the rotary table 20, it is to be understood that the kelly and rotary table could be replaced by a power swivel (not shown) in a manner well known to the art. The derrick 16 is positioned over a drilling slot, or well 26, which extends vertically through the vessel in a conventional manner. When using the equipment of the present invention, the slot 26 in the barge 11 may be either centrally located or extending from one edge. However, drilling operations may be carried out over the side of the barge without using a slot. It is also to be understood that in some areas the apparatus and method of the present invention may be utilized when operating from either a permanently fixed platform, or a temporarily fixed and normally floatable platform. However, for purposes of illustration, the present invention will be described with regard to its use when drilling and completing a well from a floating barge which is preferably anchored but not necessarily so. In many drilling operations, the floating vessel may be maintained in a relatively fixed position on the surface of the ocean by means of two or more outboard motors or other marine propulsion units arranged to act in our position.

The operating deck 21 of the offshore structures provided with a vertical opening 27 while the lower or auxiliary deck 23 is provided with a second vertical opening 28. Both the first and second openings 27 and 28, respectively, are in vertical axially alignment. The operating deck 21 may also be provided with support beams 30 and 31 on opposite sides of the first opening 27 for supporting the rotary table 20 thereon. If desired, the high beams 30 and 31 may be removably secured to the deck 21 so as to give a larger opening through the deck when lowering large equipment down to the underwater wellhead. Preferably, the spacing between the operating

deck 21 and the auxiliary deck 23 is substantially equal to a normal length of pipe, say 20 feet, used to make up a drill string 24. Thus, the elevator 19 may be able to engage and suspend the upper end of the pipe section while the lower tool joint was being made up or broken on the auxiliary deck level.

The pipe-engaging and supporting apparatus used on the auxiliary deck 23 in supporting the pipe string 25 is preferably a slip-and-spider assembly 22 of any conventional design. The slips 32 are wedge shaped elements having handles 34 to facilitate wrapping them around the pipe 25 and inserting them into the hinged casing spider 22. The spider is provided with suitable handles 35 whereby it may be pulled apart along joint 36. When not in use the casing spider 22 may be opened and pulled to one side of the opening 28 through the auxiliary deck 23 by sliding it along the deck or in any other suitable manner, as will be described hereinbelow. One suitable type of a casing spider is manufactured by the Baash-Ross Tool Company of Houston, Texas, and is described in the Composite Catalog of Oil Field Equipment and Services, 1962-63 edition, page 331. Suitable casing slips for use with the casing spider are described on 332 of the same publication.

In FIGURE 2 another arrangement of pipe suspension means are diagrammatically illustrated. The auxiliary deck 23 and its pipe suspension equipment is identical with that described with regard to FIGURE 1 with slips 32 engaging the large diameter pipe string 25 while being positioned within the casing spider 22. On the operating deck 21, the master bushing 26 (FIGURE 1), if required, is removed from the rotary table 20 and is replaced by casing supporting table bushing (not shown). A set of slips 38 having handles 39 are in pipe-supporting engagement with the table bushings for supporting the smaller pipe 24, the latter being positioned in the vertical opening through the rotary table 20. This leaves the elevator 19 free to engage the upper end of the pipe string 24 as desired, or to support a tool or a third string of pipe if desired.

One form of a slip-and-spider assembly is shown in greater detail in FIGURES 3 and 5. As shown in FIGURE 5 the casing spider 22 is made of two parts spread along lines 40 and provided with a hinge pin 41 at one end a lock pin 42 at the other end. Thus, to remove the casing spider 22 from around a pipe section passing therethrough, the lock pin 42 would be pulled out and the two sections of the casing spider 22 would be opened along line 40 while pivoting on the pivot pin 41.

To facilitate moving the casing spider 22 from its position over the opening 28 through the auxiliary deck 23, as shown in FIGURE 3, the casing spider 22 is preferably positioned on a small platform 44. The platform 44 for supporting the pipe engaging slip-and-spider assembly 22 is arranged in a readily movable manner in any suitable manner, as by mounting it on wheels to move it laterally on the auxiliary deck 23 or providing it with a hinge 45 adapted to be secured to a cooperating hinge 46 welded to the deck 23, the hinges being connected by means of a hinge pin 47 extending horizontally. The other end of the platform 44 may be secured to the deck 23 by any suitable means, as by a removable bolt 48.

As shown in FIGURE 5 the platform 44 is preferably bifurcated having laterally extending arms 50 and 51 arranged in parallel spaced relationship and of the length to stand the opening 28 through the auxiliary deck 23. As may be seen in FIGURE 3, the pivot pin 41 extends entirely through the casing spider 22 and is fixedly secured at its lower end to the platform 44 so that the casing spider 22 remains on the top of the platform 44 when the latter is raised to its vertical position as shown in FIGURE 4. The platform 44 or casing spider 22 may rest against a suitable support 52 on the drilling vessel and the equipment may be maintained in place in any

suitable manner as by ticing it back with a rope 53 connected to a ring 54.

In moving the casing spider 22 and its platform 44 out of the way when a pipe string was extending down through the opening in the auxiliary deck 23 of the vessel, the lock pin 42 (FIGURE 5) would be pulled up and the two halves of the casing spider 22 opened after the slips had been removed therefrom. The two halves of the casing spider 22 would be pulled back until they were stopped by locks 55 and 56 welded to the top of the platform 44. The platform 44 would then be raised to its vertical position as shown in FIGURE 4 with the casing spider resting against the blocks 55 and 56.

While the normal pipe engaging and supporting means for use on the operating deck 21 would comprise slips 38 being used in conjunction with the rotary table 20 as described with regard to FIGURE 2, if desired, the rotary table 20 may be removed and substituted for a second casing spider diagrammatically represented by element 58 as surrounding the pipe string 24 extending up through the opening 27 in the operating deck 21 (FIGURE 3). A split type casing bushing 59 having handles 60 may be inserted in the casing spider in a manner well known to the art with use of smaller diameter pipes, it being understood that a suitable set of slips similar to those described with regard to slips 32 would be inserted in the pipe string 24 and the casing bushing 59 when it was desired to support the pipe string 24 therein.

This application is a continuation-in-part application of copending application Serial No. 79,842 filed December 30, 1960.

We claim as our invention:

1. An offshore structure for carrying out well drilling and completion and well work-over operations, said structure adapted to be positioned at a selected offshore location in a manner sufficiently stationary to carry out operations wherein pipe means may be supported at two vertically-displaced levels, said structure comprising

an operating deck having a vertical first opening therethrough of a size sufficient to pass well tools and equipment therethrough.

an auxiliary lower deck positioned below said operating deck and having a vertical second opening therethrough at least similar in size to said first opening in said operating deck and in vertical alignment therewith,

first pipe-engaging means supported by said operating deck and arranged concentrically relative to said first opening in said deck,

second pipe-engaging means carried by said auxiliary deck and adapted to be positioned concentrically relative to said second opening in said auxiliary deck,

said second pipe-engaging means being movably positioned on said auxiliary deck for movement into and out of alignment with said opening in said deck, and movable platform means interposed between said second pipe-engaging means and said auxiliary deck for movement into and out of alignment with said opening in said deck for supporting said second pipe-engaging means.

2. The apparatus of claim 1 including vertical pivot pin means securing said second pipe-engaging means to said movable platform means.

3. The apparatus of claim 1 including horizontal pivot pin means in engagement with one side of said platform means and said auxiliary deck to one side of said second opening therethrough whereby said platform means is movable from a horizontal position to a substantially vertical position.

4. The apparatus of claim 3 wherein said platform means is bifurcated with arms extending on either side of the axis of said second opening through said auxiliary deck.

5. The apparatus of claim 4 including vertical pivot pin means in engagement between said second pipe-engaging

means and said platform means at a point intermediate said horizontal pivot pin means thereof and the axis of said second opening through said auxiliary deck.

6. The apparatus of claim 1 wherein said offshore structure is a floating structure at least when being moved to an offshore location. 5
